DEMOUNTABLE BACK REST FOR DIVAN-BED COMBINATION

James R. McKay, White Plains, N. Y.

Application October 8, 1941, Serial No. 414,173

7 Claims.

(Cl. 5—12)

The present invention relates to a demountable back rest for use in combination with a bed to provide in effect a convertible divan or sofa. More particularly, the invention relates to a demountable back rest embodying certain novel features and devices by which it is rendered adapted to be readily mounted and securely fastened in position on a single bed so as to function as a sofa or divan or to be readily removed therefrom to permit use of the entire bed for sleeping purposes.

The invention is particularly adapted to convert a full sized single bed having the standard box springs and mattress into a comfortable divan or sofa by means of a mountable and demountable back rest having certain novel features of construction which permits attachment thereof with a minimum of effort and which assures a strong yielding support during use in combination with the bed.

It is well known that the various types of folding divan-beds and studio couches which are designed for use in apartments and living quarters having limited space require so much physical effort to convert them into beds as to defeat their very purpose in many instances, particularly in connection with their use by persons of frail physique, so that the divan-beds or couches are frequently used without transformation with resulting restless and uncomfortable sleep in preference to undergoing the trouble and exertion necessary to make them up into what is at best an unsatisfactory bed.

In connection with the use of the ordinary studio couch or day-bed, the cushions provide little comfort or support for the back because of the fact that they loosely rest upon the back edge or rear portion of the studio couch or day-bed and lean against the room wall for support. Whenever an occupant leans back against such cushions, the day-bed or couch gradually creeps or slides away from the wall until the cushions drop to the floor, resulting in discomfort and annoyance to the occupant or occupants.

The general discomfort and annoyance occasioned by the use of a day-bed or studio couch as a daytime sofa, and the physical effort required to convert or prepare such convertible divans has retarded or prohibited their general acceptance and has rendered such make-shift furniture of little value to persons desiring true comfort for both day and night service.

The invention hereinafter described provides a form of back rest which may be readily and securely fastened in such position on a bed as to

provide a comfortable and luxurious sofa or divan, even though the bed be moved or placed out away from any wall, such as in front of a fire place, for example. The means hereinafter described permits the back rest to be readily fastened into position upon a single bed with little effort and may be applied whether the bed is made up or not.

One of the objects of the present invention is to provide a form of convertible divan or sofa which by day has the appearance of a sofa or divan and which may be readily converted into a comfortable single bed having luxurious standard bed springs and mattress without the necessity of stripping or making the bed.

Another object of the invention is to provide a form of convertible divan-bed or sofa-bed combination which is adapted to be readily changed from the form in which it is adapted for a divan or sofa into a bed without in any way disturbing the bed structure or changing or otherwise interfering with the bed as made up.

Another object of the invention is to provide a form of convertible bed and divan combination having a structure of novel form permitting conversion of the divan into a bed or vice versa by merely detaching or attaching, as the case may be, a back rest of novel light construction which is adapted to give ample back support when combined with the bed as hereinafter described to form the divan or sofa combination.

Another object of the invention is to provide a form of back rest which may be readily attached to the type of single bed having no head or foot boards and in which the legs are fastened directly onto the box springs, so that the back rest may be mounted directly over the mattress or on the bed in the fully made up form.

Another object of the invention is to provide a form of demountable back rest of light weight construction material, such as a light wood, a reinforced fibre board material, a plastic composition, or a light weight metal structure, which may be mounted upon a single bed without substantial physical exertion and which may be fastened in such a manner as to permit the bed and back rest combination to be fully covered with the usual slip cover or removable upholstery material to conceal the fastening means and to generally improve the appearance of the divan-form combination.

With these and other objects in view, which will appear from the following detailed description, the invention comprises the various fea-

tures and combinations hereinafter set forth and defined in the annexed claims.

The various features of the invention are illustrated in the accompanying drawings showing the invention in its preferred form, in which:

Fig. 1 is a view in perspective showing the demountable back rest of my invention as combined with or mounted on a single bed having the usual box spring and mattress but without a head or foot board, the right side of the assembly being shown with the slip cover in place;

Fig. 2 is a cross sectional view in elevation taken on the section line 2—2 of Fig. 1;

Fig. 3 is a cross sectional view in elevation taken on the section line 3—3 of Fig. 1;

Fig. 4 is a fragmentary detailed sectional view taken on the section line 4—4 of Fig. 3;

Fig. 5 is a fragmentary plan view on a reduced scale showing the under side of the back rest from the right in Fig. 1, illustrating the preferred form of construction of the lower supporting surface for the back rest;

Fig. 6 is a front view in elevation showing a portion of the preferred form of fastening means for attaching the back rest in place on the bed structure; and

Fig. 7 is a detailed view in side elevation of the portion of the fastening means illustrated in Fig. 6.

Referring more in detail to the drawings, the numeral 2 designates the demountable back rest of my invention, having arm rests 4 and 6 which are preferably connected to the bottom portion 5 of the back rest and spaced a suitable distance from the front frame portion 8, which serves to support a number of cushions as 10, 12 and 14, as shown in Fig. 1 of the drawings.

The rear end of the back rest is preferably provided with a member 16 which is preferably vertically arranged so as to be parallel with the rear marginal portion of the single bed 18 on which it is to be mounted. The forward portion 8 and the rear portion 16 of the back rest are preferably connected with an upper member 20, which with the end members 22 and 24 serves as a spacing means for holding the main supporting members 8 and 16 in place.

The arm members 4 and 6 are preferably hollow and of a form to give support and comfort to the occupants leaning against the arm rests. The underside of the frame work structure is preferably provided with a series of longitudinal members 26 and 28 and with one or more transverse members as 30, as indicated in Fig. 5 of the drawings, to serve in part as a supporting surface for the back rest when positioned on the mattress 32 of the bed structure. The longitudinal and transverse members, as 26, 28 and 30, may be provided on the underside, which is to contact with the bed surface, with suitable padding 34, 36 and 38 in order to prevent creasing or injury to the bed clothes through constant use of the back rest on the bed.

The rear lower edge of the back portion 16 and the lower outer side portions 40, 42 and the front portions 44 and 46 of the side members are preferably outwardly flanged so as to extend over the marginal edges of the mattress 32 or the corresponding made-up bed portions and to prevent slipping or sliding of the back rest when attached as hereinafter described.

It is to be understood that the lower supporting surface of the back rest may be varied as desired and may be made in one integral member extending over the entire surface of the bot-

tom of the back rest if desired. By the use of the transverse and longitudinal members as above described, however, the interior portion of the back rest is rendered accessible through the openings at the bottom between the said members so as to provide access to a storage space in the interior of the back rest for the storage of pillows, blankets and other accessories.

The back rest above described may be connected to a single bed preferably in the made-up form by suitable adjustable attaching means of a form which may be connected with the desired or variable tension and which are of a form which may be concealed by means of a couch cover or slip cover extending over the entire back rest and bed to which it is attached. The fastening means hereinabove described may be readily operated and fastened or unfastened by one person without substantial physical exertion, so that the back rest may be readily attached to a bed which has been made up, or easily removed from the bed to render it available for sleeping by a minimum number of movements which may be readily carried out by one person.

The preferred form of fastening means comprises adjustable straps 48 and 50 connected to a ring member 52 and which in turn is connected to a hook member 54 at a pivot 56. The hook member is preferably provided with a handle 58. The strap members 48 and 50 are preferably arranged to engage in openings 60 and 62 in the side portions 40, 42 of the back rest member and buckles 64 and 66 are preferably provided in the strap members so as to permit adjusting the effective length of the straps, by which the amount of force necessary to fasten the back rest in place on the bed structure may be determined or adjusted. In order to fasten the hook member in place, a female or hook-engaging member 68 is provided having a plate portion 70 adapted to be screwed or otherwise fastened to the lower frame portion 72 of the bed 18 at substantially the mid portion thereof as illustrated in Fig. 1 of the drawings. The hook-engaging member 68 is preferably formed with a fixed fulcrum for the lever in such relative positions that the lever may be passed beyond the dead-point or center-line into holding or clamped position. For this purpose, the hook-engaging member 68 is preferably formed with an upwardly extending hook portion or curved portion 74 and guide members 76, 78 at the lower portion thereof so that when the hook portion 80 of the male member 54 is inserted under the hook portion 74 of the plate member 68, the ring member 52 and strap members 48 and 50 are forced downwardly in tension, whereby as the handle 58 is thrust inwardly between the guide members 76 and 78, a lever action around the hooks 80 and 74 as a fulcrum is provided, by which the lever is seated and the back rest is fastened, one end at a time, over the bed.

If it is desired to employ a single integral bottom member 5 for supporting the back rest together with the outwardly extending side portions under the arm members 4 and 6, access to the interior storage space 82 in the interior of the back rest may be obtained by the use of a hinged top member 20, which may be hinged along the rear edge, for example, and be provided with a catch or locking member at its forward edge if desired. It is to be understood, however, that the open construction as illustrated in Fig. 5 is ordinarily preferred, so that

access to the storage space **82** may be provided between the longitudinal and transverse bottom members without the use of hinges and locking devices above referred to.

It is to be understood that the back rest may be fastened into place on the bed structure when the bed clothes are in place on the mattress **32** and the bed is made up in the usual way, so that the bed will be immediately available for sleeping purposes by the mere removal of the back rest.

When the back rest is in place on the bed, a snugly fitting couch cover or slip cover **84** of suitable fabric may be placed over the entire back rest and bed so as to completely cover them, thus concealing the straps or fastening means by which the back rest is held in place.

It is to be understood that the cushions **10**, **12**, **14** may be of any suitable material such as the commonly used latex airfoam and the padding **34**, **36** and **38** may also be of the same material, if desired, to support the weight of the back rest against the upper surface of the bed. It will also be understood that the dimensions of the back rest may be varied as desired to fit a bed of any given dimensions and to provide the desired amount of seating surface in front of the front supporting surface **8**, or more properly in front of the back cushions **10**, **12** and **14**.

It will be understood that in the preferred form of the invention the marginal portions around the bottom **5** of the back rest which extends over the margins or edge portions of the bed or mattress may be rounded or flanged so as to provide a slight clearance to provide for slight deviations in the mattress or bed size, so that the edge portions of the back rest extend out beyond the sides and the back portions of the mattress or bed. If the bed is made up, the flanged portion extends outwardly to a sufficient extent so as to fit over the edges of the made-up bed.

While the preferred form of the invention employs only two fastening members of the Y-form as illustrated in Fig. 1 of the drawings in which the branches of the Y are spread sufficiently so that there is an equal pull from each side of the center line of the back rest member toward the plate member **10** or fulcrum **80**, it will be understood that additional fastening means may be employed if desired in specific installations. I may for example employ a similar fastening means **84** at the mid-portion of the rear flange **86** in which the fastening means is similar to that already described, or if desired, a single strap may be used attached to a ring member similar to **52** and secured in position in a manner similar to that already described. A similar strap member may also be attached at the front of the back rest at the portions **44** and **46** of the side or end members if desired, although in the ordinary installations the additional holding straps are not required.

It will be apparent, therefore, that various changes or modifications may be made in the details of construction of the demountable back rest and the means for fastening the same to a bed without departing from the spirit or scope of the invention as defined in the annexed claims. In certain installations, where desired, I may omit the arm rests **4** and **6** entirely and in this form of construction the fastening means may comprise a single strap connected to each end of the back rest member and to a lever member which may be seated on the bed member as described above, or if desired I may employ the

Y-form of fastening means for holding the back rest member in place on the bed member. In either instance, the strap members should be substantially centered, and if the Y-form of fastening is employed the straps **48** and **50** should be attached to the back rest frame at the ends at substantially equal distances from the end center lines so as to distribute or substantially equalize the holding forces in a forward and rearward direction laterally of the back rest so as to securely hold the same in place on the bed member.

While the fastening means for securing the back rest member in place on the bed member has been described as having the plate member and fulcrum thereon secured or connected to the bed member, and the straps and lever or tightening means secured to the back rest member, it will be apparent that these may be reversed in position so that the lever means, for example, is connected to the bed member and the fulcrum means is connected to the back rest member. I desire, therefore, not to be limited to the form of construction and the position of the parts as illustrated in the preferred embodiment of the invention as described, but the parts and positions thereof may be varied as will be apparent to those skilled in the art without departing from the invention as defined in the claims.

Having thus described the invention, what is claimed as new is:

1. A back rest structure adapted to be mounted on a single bed comprising a bottom supporting surface, a rear vertical member, a supporting surface forwardly thereof and inclined rearwardly, a top member joining the said vertical member and forward supporting surface, arm members extending upwardly from said bottom supporting surface, outwardly extending flanged portions adjacent said bottom supporting surface, an opening in said bottom supporting surface to provide access to storage space between said vertical member, said supporting surface forwardly thereof and said top member, openings in said flanged portions, adjustable strap members connected to said openings and lever means for forcing said strap members downwardly to hold said back rest in place.

2. An article of furniture of the kind described comprising in combination a bed member, a demountable back rest member of light construction having forwardly extending arms at the side portions of the back rest member, said back rest member extending longitudinally the entire length of the bed member and laterally under said forwardly extending arms the entire width of the bed member so as to leave exposed on the bed surface ample seating space between said arms forwardly of the back rest member, said back rest member having marginal flange portions extending over the marginal edges of the bed member, means for securing the back rest member in position on said bed member including strap members in the form of a Y attached to the side marginal flange portions, lever means connected to said strap members, pivot means serving as a fulcrum for the lever means connected to the bed member, and guide means connected to said bed member for guiding said lever means into seating position to securely hold the back rest member in place.

3. An article of furniture of the kind described comprising in combination a bed, a demountable back rest of light construction having back, front

and top members serving to include a storage space therebetween, forwardly extending arms at the side portions of the back rest, said back rest extending longitudinally the entire length of the bed and laterally under said forwardly extending arms the entire width of the bed so as to leave exposed on the bed surface ample seating space between said arms forwardly of the said front member, said arms being spaced from said front member a sufficient distance to permit the use of cushions therebetween, said back rest member having marginal flange portions extending over the marginal edges of the bed, means for securing the back rest in position on said bed including strap members in the form of a Y attached to the side marginal flange portions, a lever connected to the lever ends of the strap members, pivot means serving as a fulcrum for the lever connected to the ends of the bed and guide means connected to said bed for guiding the lever into seating position between the guide members to securely hold the back rest in place on the bed.

4. A demountable back rest structure for use in combination with an open top bed to provide a sofa, comprising a rear supporting element of bed length and of a width to cover a substantial portion of the rear top surface of the bed, said supporting element having a portion at each end thereof of a length to extend forwardly to the front edge of said bed surface and of a width to form a base support for an arm rest, a back rest member mounted on the rear supporting element and an arm rest member mounted on each arm rest support, said back rest member comprising a forward wall element extending upwardly along the front edge of the said rear supporting element and means concealing the said rear supporting element said forward wall element and adjustable fastening means for securing said structure upon said bed.

5. An article of furniture of the kind described comprising in combination an open-top bed having no head or foot boards, a demountable back-rest member having a longitudinally extending back-rest portion and transverse arm-rest portions combined therewith in a unitary structure so as to leave a free open portion between the said arm-rest portions, said unitary back-rest and arm-rest portions being mountable as a unit on said open-top bed so as to expose a free seating

surface on the bed between said arm-rest portions forwardly of said back-rest portion, fastening means attached to the ends of the back-rest member and attachable to the ends of the said open-top bed so as to resist displacement of the back-rest member when in mounted position on said bed and means for varying the effective length of said fastening means to control the amount of force required to fasten the back-rest member in place on said open-top bed.

6. An article of furniture of the kind described comprising in combination an open-top bed having a box spring and mattress without head or foot boards, a demountable back-rest member having a longitudinally extending back-rest portion and transverse forwardly extending arm-rest portions combined therewith in a unitary structure so as to leave a free open portion between the arm-rest portions, said unitary back-rest and arm-rest portions being mountable as a unit on said open-top bed so as to expose a free seating surface on the bed between said arm-rest portions forwardly of said back-rest portion, each of said arm-rest portions having a flat under surface adapted to rest on the adjacent bed surface and a marginal flange extending outwardly from said under surface of the arm-rest portions so as to extend over the adjacent marginal end-portion of the bed and adjustable forked fastening means carried at the end portions of the back-rest member for attaching the back-rest member to the end portions of the bed.

7. An article of furniture of the kind described comprising in combination an open-top bed, a demountable back-rest of unitary structure having a back portion and forwardly extending arms at the sides thereof leaving a free open space between said arms, each of said arms having a flat under surface adapted to rest on the adjacent bed surface and an outwardly extending flange at the lower outer side of each of said arms adapted to extend over the adjacent marginal end of the bed to prevent longitudinal slipping of the back-rest in attached position, an adjustable fastening means in Y-form carried at least in part by the said back rest and mounted so as to be connected at the ends of the bed to the corresponding adjacent back-rest portion and lever means forming part of said fastening means for connecting said fastening means in adjusted position.

JAMES R. MCKAY.
